UNITED STATES PATENT OFFICE

163,555

COASTER WAGON

Charles Bakerman, Albany, N. Y.

Application June 29, 1950, Serial No. 10,837

Term of patent 3½ years

(Cl. D34—15)

To all whom it may concern:

Be it known that I, Charles Bakerman, a citizen of the United States, residing at Albany, in the county of Albany and State of New York, have invented a new, original, and ornamental Design for Coaster Wagon, of which the following is a specification, reference being had to the accompanying drawing, forming part thereof.

The figure is a view in perspective of a coaster wagon, illustrating my new design.

I claim:

The ornamental design for a coaster wagon, as shown.

CHARLES BAKERMAN.
